UNITED STATES PATENT OFFICE.

JOHN LYNN EBAUGH, OF NEW ORLEANS, LOUISIANA, ASSIGNOR TO MERCANTHALER LINOTYPE COMPANY, A CORPORATION OF NEW YORK.

LINOTYPE-MACHINE.

SPECIFICATION forming part of Letters Patent No. 735,226, dated August 4, 1903.

Application filed June 1, 1903. Serial No. 159,699. (No model.)

To all whom it may concern:

Be it known that I, JOHN LYNN EBAUGH, of New Orleans, parish of Orleans, and State of Louisiana, have invented a new and useful Improvement in Linotype-Machines, of which the following is a specification.

My invention relates to an improvement in the expandable wedge-spacers or justifiers of the Schuckers type, broadly covered by United States Patent No. 474,306, as used in the Mergenthaler linotype and analogous machines. In the Mergenthaler machines these spacers are arranged to circulate from their magazine to the composed line and thence in the line to the casting mechanism and finally back to the magazine. They consist each of a short wedge to be inserted and locked in the line and a longer wedge carried by the first and connected thereto by a vertical sliding joint, so that the longer wedge may be thrust upward through the composed line to expand or elongate the same and effect the justification. In the operation of the machine these composite spacers are dropped into the line in the course of composition from above, entering the same between the star-wheel or pusher and the matrix last added to the line. In practice it is sometimes found that the spacers will hesitate in descending to their final positions in the line, because their thick lower ends do not pass readily between the star-wheel and the end of the line. It is also found that the lower ends of the spacers entering abruptly to their full thickness between the line and the star-wheel tend to wear and mutilate the latter and also cause the line to be forced forward with a violent action. In order to overcome these difficulties, to ease the action of the parts, and to reduce the wear and increase the speed of assemblage, I round or taper the lower end of the spacer by gradually reducing its thickness toward the lower end, preferably on the side distant from the star-wheel or pusher.

The essence of the invention resides in tapering the spacer or reducing its thickness toward the lower end. The form of the reduced portion and the extent of the reduction may be varied at will provided the mode of action herein described is retained.

Figure 1 is a face view of my improved

spacer; Fig. 2, an edge view of the same; Fig. 3, a front elevation illustrating the manner in which the spacers enter the line; Fig. 4, a rear elevation of a matrix-line containing a spacer with the movable member at its extreme elevation.

Referring to Figs. 1 and 2, A represents my improved spacer, consisting of the two members or wedges *a* and *a'*, tapered in opposite directions. The upper and shorter wedge *a* is formed with ears extending edge-wise from the upper end for the purpose of supporting and locking it in the composed line as usual. The longer wedge *a'*, having its thin end uppermost, is provided with a longitudinal dovetail slot which receives a corresponding tongue on the part *a*, the sliding joint or connection thus formed serving to hold the two parts together and to adapt the shorter member to carry the longer, while at the same time permitting the long member to be thrust upward through the composed line past its companion in order to increase the thickness of the operative portion in the line. As far as described the spacer is of ordinary construction familiar to those skilled in the art.

Heretofore the member *a'* has been made of increasing thickness to its extreme lower end, or practically so, as indicated by dotted lines in Fig. 2. My improvement consists in beveling or cutting away the member *a'* on its side face, reducing its thickness toward the lower end. This beveling may begin half an inch, more or less, above the lower extremity and the beveled surface may be flat or rounded. The effect of thus beveling the member *a'* is to give it its maximum thickness at a point some distance above the lower end and to cause it to present a thin lower end to enter between the assembler-wheel and the matrix-line.

In Fig. 3, C represents a partially-composed line of matrices; D, a rotary star-wheel by which the descending matrices and spacers are pushed forward successively against the line and the line moved bodily forward. In this figure I have shown one of my improved spacers descending to its place in the line in front of the wheel. As the spacers must close the space between the adjacent matrices

- tightly in order that molten metal may not enter between them during the casting action, it is obvious that the beveled or rounded surface must be so limited in length that it will not under any circumstances be carried upward between the matrices to the casting point. In Fig. 4 I have shown a line of matrices containing a spacer with its member a' lifted to the highest position possible. It will be observed that the beveled portion falls wholly below the characters or matrices proper and that the beveling of the face does not affect in any manner the ordinary action of the spacer.
- 15 The essence of my invention lies in tapering or reducing in thickness the lower end of the spacer, which is moved upward through the line to effect justification, and the improvement is applicable alike to all spacers having this action without regard to their details of construction in other respects.
- The improvement is applicable to all spacers which have a thickened lower end, not only to two-part or double spacers of the Schuckers type, but also to stepped spacers, such as represented in Patent No. 565,440.
- 25 Good results are obtained by rounding the spacers on either side. The best results are secured when they are rounded on the side remote from the star-wheel, or, in other words, on the side next to the composed line of matrices, as shown in the drawings. When thus rounded, they are free from liability to over-ride or strike upon the end of the matrix-line.
- 30 35 In other words, they are certain to descend speedily and easily to their proper places at the end of the line.
- Having thus described my invention, what I claim is—
- 40 1. A spacer for a linotype-machine, consist-

ing of oppositely-tapered connecting-wedges, the lowermost wedge having its lower end reduced in thickness, substantially as described.

2. The spacer for a linotype-machine, comprising the supporting-wedge a , with its thin end lowermost, and the connected wedge a' , having its operative portion tapered in one direction, and its lower extremity tapered in the opposite direction. 45

3. The spacer or justifier, consisting of the short wedge a , and the longer wedge a' connected thereto by a sliding joint, and having its lower end beveled, substantially as shown at a^2 . 50

4. In a linotype-machine, in combination with a series of circulating matrices C and a star-wheel or pusher D, a series of composite wedge-spacers A, having their lower ends reduced in thickness to facilitate their entrance in front of the pusher. 55

5. A spacer for a linotype-machine, having its body portion of increasing thickness from the upper toward the lower end, and with the lower extremity reduced in thickness, substantially as described and shown. 60

6. In a linotype-machine and in combination with the circulating matrices and a device for assembling them in line, a series of circulating tapered spacers, arranged to enter the line from above, said spacers having their lower extremities tapered on the side remote from the assembling device. 70

In testimony whereof I hereunto set my hand this 21st day of May, 1903, in the presence of two attesting witnesses.

JOHN LYNN EBAUGH.
